MUD FLAP FOR TRUCKS

Lowell H. Fox, Fostoria, Ohio, assignor to Roppe
Rubber Corporation, Fostoria, Ohio

Filed Feb. 26, 1975, Ser. No. 553,414

Term of patent 14 years

Int. Cl. D12—16

U.S. Cl. D12—185

FIG. 1

FIG. 2

FIG. 3

FIG. 4

FIG. 5

FIG. 1 is a perspective view of a mud flap for trucks showing my new design;

FIG. 2 is a front elevational view thereof;

FIG. 3 is a typical side elevational view thereof;

FIG. 4 is a rear elevational view thereof; and

FIG. 5 is a bottom plan view thereof.

I claim:

The ornamental design for a mud flap for trucks, as shown.
